(57) **CLAIM**

The ornamental design for a mobile communication terminal, as shown and described.

DESCRIPTION

FIG. 1 is a front perspective view of a mobile communication terminal showing my new design according to a first embodiment;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of a mobile communication terminal showing my new design according to a second embodiment;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a front perspective view of a mobile communication terminal showing my new design according to a third embodiment;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof; and,

FIG. 21 is a bottom plan view thereof.

The evenly-spaced dashed broken lines in the figures depict portions of the mobile communication terminal that form no part of the claimed design.

The unevenly-spaced dot-dash broken lines in the figures depict the boundaries of the claimed design and form no part thereof.

1 Claim, 15 Drawing Sheets
